MEANS FOR SHARPENING SERRATION CUTTERS

Alvin Jantz, Newton, Kans., assignor to Boeing Airplane Company, Wichita, Kans., a corporation of Delaware

Application December 5, 1956, Serial No. 626,337

5 Claims. (Cl. 51—105)

My invention relates to means for sharpening serration cutters. More specifically, means are shown to modify a conventional helical thread grinder for automatic grinding of serration cutters.

Automatic thread grinders adapted to cut and sharpen helical threads are presently in use and have resulted in large savings. However, no means have been provided to perform similar automatic operations on serration cutters. A serration cutter may be defined as a cutter for cutting serrations having teeth disposed in a plurality of rows, the rows being parallel to the cutter axis, and the teeth in the rows being oriented in circumferential files substantially at right angles to the cutter axis. To sharpen the serration cutters on conventional thread grinders before this invention, it was necessary to manually reset the grinder for each circumferential file, the number of settings depending on the number of files.

The thread grinders are normally adapted to grind helical threads by rotation of a workpiece between head and tail stock center spindles by a dog connected to a rotating head member. While the workpiece is rotated, the head and tail stocks are advanced laterally of the periphery of a grinding wheel whereby the actual cut is in a helical pattern.

The objectives of my invention include: to devise improved means for sharpening serration cutters; to provide means for automatically sharpening such cutters; to provide an attachment for a standard thread grinder to automatically grind such cutters; and to provide the above in an economical structure which is accurate and efficient of operation and preferably automatic after initial setting.

My invention will be best understood, together with additional objectives and advantages thereof, from a reading of the following description, read with reference to the drawings, in which:

Figure 1 is a perspective view showing certain components of a thread grinder and showing a specific embodiment of my invention installed in the thread grinder;

Figure 2 is an enlarged side elevation of a portion of the head assembly incorporating cam means, portions being broken away and shown in section;

Figure 3 is a fragmentary, enlarged side elevation of the cam and cam follower of said cam means;

Figure 4 is a side elevation of the head stock assembly with portions broken away and shown in section and with portions of the head stock being shown in phantom or omitted;

Figure 5 is an enlarged, fragmentary view taken on line 5—5 of Figure 4; and

Figure 6 is an enlarged, fragmentary view of portions of a serration cutter and grinding wheel.

Figure 1 shows my invention as incorporated in a conventional automatic thread grinding machine. The structure shown follows that of the model TG-1245 thread grinder of Jones & Lamson Machine Company, Springfield, Vermont. However, the invention is adaptable to other thread grinders on the market. Only a brief description will be given of the thread grinder as such machines are well known to the art.

The machine includes a base 10 and a table 12 which is mounted for rectilinear movement on the base. This movement, together with rotation of the workpiece,

causes a grinding wheel 14 to normally make a helical cut on the workpiece. Means are provided to power the assembly for these movements which are closely controlled so that an exact type of threaded body can be produced. The same power means and controls can be used for automatic operation when the thread grinder is adapted to cut serration cutters as hereafter described.

Head and tail stocks 16, 18 are mounted on table 12 and are adjustable in position to accept various types of work. Head and tail center spindles 20, 22 rotatably support the work and the tail center spindle 22 is slidably mounted in tail stock 18 and is urged against the work by a compression spring 24. A rotating head member 30 is connected to the work by a dog 32 attached to an adjustable driving face plate or fixture 34.

Figure 4 shows in simplified, semidiagrammatic form some principal components of the head assembly. Rotating head member 30 is attached to a tubular head member 36 which is rotatably supported by bearings 38, 40. A gear 42 is secured to tubular member 36 and is driven by a spur gear 44 attached to a drive shaft 46.

The tubular head member 36 is provided in this machine principally so that work too long to normally be supported between the head and tail stocks may be inserted through member 36 to position an inner end portion in the normal location of a workpiece. Although my structure can be adapted to machines not having this hollow head member, its presence is convenient for the installation of my invention.

A housing 50 is frictionally secured in tube 36 by having a relative taper therebetween. Head center spindle 20 is slidably mounted in housing 50. An oil seal is formed on the inner end by the resilient washer 52 and a backing ring 54 secured by screws 56. A split ring 58 is secured on spindle 20 by a clamping bolt 60 and ring 58 carries a cam follower 62. Cam follower 62 is a rod-shaped body secured as by welding or brazing in a V-groove seat 61 formed in a boss 63 on ring 58. An end plate 64 is secured to the outer end of housing 50 by bolts 66 and an oil seal is formed by a resilient washer 68 and a backing ring 70 secured thereto by rivets 72.

Plate 64 carries an annular cam 74. Cam 74 has a single rise 76 and the cam makes a straight line progression between the start and the peak of the rise. The cam is formed to exactly retrogressively compensate for the movement of table 12 relative grinding wheel 14 during each rotation of rotating head member 30 so that the serration cutter 78 is held in a fixed position longitudinally of base 10. When follower 62 strikes rise 76 the cutter is moved the full distance that the table has moved relative the grinding wheel during that rotation.

In Figure 5, cutter 78 is shown in full lines in the position where grinding wheel 14 is engaging between teeth in one row 80 of the teeth. When cutter 78 is originally positioned it is located so that the cutter teeth will be in the position shown in dotted lines in Figure 5 when follower 62 strikes rise 76 so that the teeth will clear the grinding wheel during this relative movement. The advancement of cutter 78 by the action of cam 74 is equal to the space x (Figure 6) between the circumferential files of teeth 80.

Head spindle 20 has sliding movement relative head stock 16 during each rotation and follower 62 is pressed against cam 74 by compression spring 24. Head center spindle 20 is held against rotation by a lateral arm 82 secured to the end of a spindle extension 84 which is pivotally connected to spindle 20 by pivot pin 89. A cap member 85 secured to the end of tube 36 by set screw 87 supports the outer end of spindle extension 84. Lateral arm 82 is split and clamped to the end of extension 84 by a clamping bolt 86. Arm 82 is jointed and a pivot bolt 88 may be tightened sufficiently to normally hold

the articulated end 90 in position but the end may be manually forced into and out of engagement with the bifurcation 92 of a bracket 94 secured to head stock 16 by a bolt 96.

The operation of my invention is as follows: serration cutter 78 is mounted between head and tail spindles 20, 22. The cam plate 64 used has a cam rise 76 equal to the space x between circumferential files. Cam plates 64 may be interchanged according to the cutter to be sharpened. The thread grinder is set to advance table 12 relative base 10 a distance equal to x during each rotation of rotating head member 30. Cam rise 76 is located to be struck at the dotted line position of the serration teeth shown in Figure 5 of the drawings so that the grinding wheel may be passed. When other parts are located, then the pivotal end 90 of lateral arm 82 is engaged in the bifurcated bracket 94. These settings being accomplished, the machine will automatically grind the serration cutter and will consecutively locate grinding wheel 14 in line with each space between circumferential files of the serration teeth.

The standard thread grinding machine has a radial relieving attachment which reciprocates the grinding wheel toward and away from the workpiece. This attachment will not be described as it is well known and is used in cutting taps. The function of the attachment is to cut more deeply at the rear side of the tooth than at the forward edge so that the tooth may perform a cutting function. This radial relieving attachment is used in cutting the present serration cutters and is set according to the number of teeth on the cutter to obtain radial relief.

Having thus described my invention I do not wish to be understood as limiting myself to the precise details of construction shown, but instead wish to cover those modifications thereof which will occur to those skilled in the art from my disclosure and which fairly fall within the scope of my invention, as described in the following claims.

I claim:

1. Means for adapting a thread grinder to grind a serration cutter in which teeth disposed in a plurality of rows are oriented in circumferential files substantially at right angles to the cutter axis, the thread grinder being normally adapted to grind helical threads by rotation of a workpiece between head and tail stock center spindles by a dog connected to a rotating head member while the head and tail stocks and a grinding wheel have relative movement whereby the workpiece is advanced laterally of the wheel periphery, comprising: a housing secured in said rotating head member to rotate therewith, said head center spindle being slidably mounted in said housing and means connecting between said head spindle and a portion of said head stock holding said head spindle against rotation, said tail stock having spring means positioned to act on said tail center spindle and annular cam means in said housing acting between means in said housing and means on said head spindle pressed into engagement by said spring means forcing the tail center spindle toward the head stock, said cam means being retrogressive at all but one point in each rotation of said rotating head member backing said head center spindle toward said head stock at the same rate that the head and tail stocks are moving relative said grinding wheel whereby the cutter is held with a circumferential file in a fixed plane relative the grinding wheel, and the cam means at said one point in each rotation having a sharp rise moving the head center spindle a progression equal to the advancement of the head and tail stocks relative the wheel during the rotation and equal to the space between circumferential files.

2. The subject matter of claim 1 in which said annular cam means includes an annular cam secured in the end of said housing opposite to the tail stock and a cam follower secured to said head spindle and disposed in said housing in position to engage said cam.

3. The subject matter of claim 1 in which said rotating head member in said head stock includes a hollow tube-shaped member extending substantially through said head stock, the housing being circular in cross-section and being secured in said tube-shaped member by a relative taper therebetween, said head spindle extending beyond said housing to the outer end of said tube-shaped member, and said connecting means between said head spindle and said head stock being a lateral arm secured at one end to said head spindle and having its other end slidably retained in a bifurcated bracket on the head stock, said lateral arm having a joint for forceable moving of the arm to engage in and withdraw from the bifurcated bracket during positioning of the serration cutter.

4. Means for adapting a thread grinder to grind a serration cutter in which teeth disposed in a plurality of rows are oriented in circumferential files substantially at right angles to the cutter axis, the thread grinder being normally adapted to grind helical threads by rotation of a workpiece between head and tail stock center spindles by means connected to a rotating head member while the head and tail stocks and a grinding wheel have relative movement whereby the workpiece is advanced laterally of the wheel periphery, said head center spindle being slidably mounted in said rotating head member and means connecting between said head spindle and said head stock holding said head spindle against rotation, cam means acting between means connected to said rotating head member and means on said head spindle, said cam means being retrogressive at all but one point in each rotation of said rotating head member backing said head spindle toward said head stock at the same rate that the rotating head member and tail stock are moving relative said grinding wheel whereby the cutter is held with a circumferential file in a fixed plane relative the grinding wheel, and said cam means at said one point in each rotation having a sharp rise moving the head spindle a progression equal to the advancement of the rotating head member and tail stock relative the wheel during the rotation and equal to the space between circumferential files.

5. Means for adapting a machine, normally used to remove material in a helical path on a threaded body or the like, to cut a serration cutter in which teeth disposed in a plurality of rows are oriented in circumferential files substantially at right angles to the cutter axis, the machine normally rotating a workpiece between head and tail stock center spindles by a rotating member in one of said stocks while the head and tail stock spindles and a cutting means have relative movement whereby the workpiece is advanced past the cutting means, comprising: a first of said stock center spindles being slidably mounted relative said rotating member and means connecting between said first spindle and a non-rotating portion of said machine holding said first spindle against rotation, cam means acting between means connected to said rotating member and means on said first spindle, said cam means being retrogressive at all but one point in each rotation of said rotating member backing said first spindle in a reverse direction and at the same rate that the rotating member is moving relative said cutting means whereby the cutter is held with a circumferential file in a fixed plane relative the cutting means, and the cam means at said one point in each rotation having a sharp rise moving said first spindle a progression equal to the advancement of said rotating member relative the cutting means during the rotation and equal to the space between circumferential files.
